UNITED STATES PATENT OFFICE.

HARRY A. FOOTHORAP, OF HARRISBURG, PENNSYLVANIA, ASSIGNOR TO ELLIOTT FISHER COMPANY, OF HARRISBURG, PENNSYLVANIA, A CORPORATION OF DELAWARE.

TYPE-WRITING MACHINE.

1,146,148.

Specification of Letters Patent. Patented July 13, 1915.

Application filed August 23, 1910. Serial No. 578,492.

To all whom it may concern:

Be it known that I, HARRY A. FOOTHORAP, a citizen of the United States of America, residing at Harrisburg, in the county of Dauphin and State of Pennsylvania, have invented certain new and useful Improvements in Type-Writing Machines, of which the following is a specification.

My present invention relates to type-writers and is more particularly directed to the improvement of that class of typewriters in which the printing is effected by means of a key-operated printing wheel.

The object of the invention is to provide simple, durable and efficient motion transmitting mechanism between the keys and the printing wheel, the primary element of such intermediate mechanism being held and guided in a manner to render accurate and certain the motion transmitted to the wheel and to present a minimum of friction and consequent resistance to the operation of the keys.

Another object is to provide means whereby the elements of the motion transmitting mechanism may be relatively adjustable in different directions in order to facilitate the accurate setting of the mechanism for the accurate spacing of the printed characters.

To the accomplishment of the recited ends and others subordinate thereto, the invention resides in the novel construction and arrangement of parts hereinafter described and illustrated in the accompanying drawings.

In said drawings—Figure 1 is a plan view of a typewriting machine constructed in accordance with my invention. Fig. 2 is a similar view with the top plate and the parts carried thereby removed and a portion of the frame shown in section. Fig. 3 is a view similar to Fig. 2 with parts broken away and showing the positions assumed by the wheel operating mechanism and the platen feeding mechanism when the wheel has been located. Fig. 3^a is a detail view showing the manner of mounting the motion retracting spring. Fig. 4 is a view similar to Fig. 3 but showing the parts in the positions they assume at the moment of printing. Fig. 5 is a transverse sectional view of the machine. Fig. 6 is a transverse sectional view on a somewhat enlarged scale, the line of section of the upper portion being at the center of the machine and the line of section

of the lower portion being taken through one of the ribbon spools, the ribbon feeding mechanism being shown in full lines in normal position and in dotted lines in the positions assumed by the parts during the printing operation. Fig. 7 is a plan view of the top plate inverted and showing the ribbon spools broken away to disclose the ribbon feeding pawls. Fig. 8 is a detail view of the rock shaft, dogs, cam plate and reversing handle of the ribbon feeding mechanism. Fig. 9 is a detail sectional view through one of the ribbon spools and its support. Fig. 10 is a section on the line 10—10 of Fig. 9. Fig. 11 is a section on the line 11—11 of Fig. 9. Fig. 12 is a detail perspective view of a ribbon spool. Fig. 13 is a longitudinal sectional view through the machine. Fig. 14 is a perspective view of one of the key-operated slides and adjacent parts. Fig. 15 is a detail view of the connection between the slide and connecting rod shown in Fig. 14. Fig. 16 is a detail perspective view of one of the keys. Fig. 17 is an inverted plan view thereof with the end of the key lever shown in section. Fig. 18 is a detail perspective view of the key top and the label frame shown separated but in juxtaposition. Fig. 19 is a section on the line 19—19 of Fig. 17 on a somewhat enlarged scale. Fig. 20 is a similar section on the line 20—20 of Fig. 17, and Fig. 21 is a detail view of the end of a key lever before the key is attached.

Each part, wherever shown, is designated by its appropriate reference character.

Mounted on a base plate 1 is a frame A which is of rectangular form, as shown in Fig. 2, and includes front and back bars 2 and 3, end bars 4 and 5 and a central transverse bar or frame member 6. The frame bar 6 is provided with guides 7 which accommodate a wheel slide or carrier 8 confined in the guides by front and rear plates 9 and 10. Upstanding from the carrier 8 is a wheel spindle 11 upon which revolves a wheel pinion 12 having vertically disposed guide pins 13 which extend into suitable openings in the type wheel 14 mounted to rotate on the spindle 11 with the pinion 12 and movable vertically to present the desired row of type faces in position for printing in a manner well understood in the art. The means for raising the printing wheel 14 to the proper height to present the row of type faces to

the printing point forms no part of the present invention, but as shown, it consists of a rock shaft 15 suitably mounted on the frame A and having an arm 16 at one end which engages the printing wheel and having an arm 17 at its opposite end which is operated by either of two keys 18.

As the type characters are distributed around the periphery of the wheel 14 in rows, it is necessary to rotate the wheel in one direction or the other to bring the desired type opposite the printing point. To accomplish this rotary movement of the wheel a vibrator 19 is pivoted at 20 on the wheel carrier 8 and includes a toothed segment 21 in mesh with the pinion 12 and normally occupying the central position indicated in Fig. 2. The vibrator 19 also includes arms 22 extended in opposite directions from its axis of movement and pivotally connected respectively by links 23 with swinging arms 24 mounted at the opposite ends of the frame. The arms 22 are adapted to coact with cam faces 25 formed at the rear edge of the plate 9. Each of the links 23 is connected by means of a connecting rod 26 with a key-operated slide 27.

Each of the slides 27 is movable between a pair of guides 28 between which and the opposite sides of the slide are interposed anti-friction members as for instance balls 29 accommodated in race ways 30 and 31 formed in the contiguous faces of the guides and slide respectively. The balls are separated by separating pins 29^a carried by the slide. The guides 28 are adjustably secured to the base plate 1 as by screws 32 passed upwardly through slots 33 in the plate 1 and into suitably threaded openings in the guides. By reason of this provision for adjusting the guides transversely an accurate adjustment of the slides in assembling the machine is facilitated and compensation for wear is secured. The adjustment of the slide is also facilitated by threading the connecting rod 26 into a swivel connection 26^a, see Figs. 14 and 15, whereby the rod may be slightly lengthened or shortened, and it is also desirable to arrange the pivotal connection 26^b of the rod 26 for adjustment along the link 23, the latter being preferably provided with a plurality of apertures 26^c for this purpose. It will now be seen that either slide 27 if urged toward the rear of the machine will cause the vibrator 19 to be swung and the printing wheel 14 to be rotated. This rotary movement of the wheel is designed to bring the desired type character at the printing point and as the type carriers are variously placed about the periphery of the wheel, a variable stop mechanism determines the degree of rotation. The primary element of this stop mechanism is a stop rack 34 meshing with the pinion 12 and mounted to move longitudinally in a guide

35. As the slide 27 moves back the rotation of the pinion 12 will cause the stop rack 34 to move toward the operated slide. The slides 27 are operated by the depression of the keys 36 which are divided into two sections the levers 37 of which converge rearwardly and are pivoted in two distinct groups in supporting brackets 38 pendent from the top plate 39 of the frame. It may be noted in passing that the top plate 39 is supported by elevated portions 39^a of the end frame members 5 and is detachably retained in place by screws 5^b.

The key levers 37 are provided with angular rear ends which constitute stop members 40 which act as wheel locating stops coacting with the stop rack 34, the stop member of every third key lever being extended sufficiently to permit its engagement with the adjacent slide 27. While this arrangement of the key levers is not novel, it may be noted that each side section of the keyboard associated with the levers of a group are divided into subsections of three keys each. The outside lever of each subsection, see Fig. 1, is the one whose stop member is extended downwardly to engage the slide 27 and whose outer end is connected to the extreme front key of the subsection. The intermediate key of the subsection is connected to the intermediate lever and overlaps the outer lever while the rearmost key is carried by the third lever and overlaps the other two. Thus the slide operating lever will be operated by the depression of any one of the several keys of the subgroup, but the movement of the stop rack 34 will be governed by the particular key depressed because said key will position a stop in the path of the rack.

For the purpose of properly guiding the slide operating portions of the key levers and to afford a backing for the side thrust imposed upon the stop members when the movement of the rack 34 is arrested, each slide is formed with parallel guideways 41 having flared entrances 42 and accommodating contact rollers 43 of graduated diameters. That is to say, the diameter of each contact roller of the series mounted in the slide is somewhat greater than an adjacent roller, the smallest roller being at the inner end and the largest at the outer end of the series. Upon the operation of a key the stop arm thereof swings rearwardly and entering one of the guideways 41 engages a contact roller 43 and rotates the adjacent slide 27 rearwardly. This through the intermediate connections causes the vibrator 19 to swing, as for instance from the position shown in Fig. 2 to that shown in Fig. 3, and before the stop member or portion of the key lever has moved beyond the rack 34, the latter will contact with the stop member, as shown in Fig. 3, thus arresting the

the rotary movement of the type wheel. Continued depression of the key and rearward movement of the slide 27 will therefore cause rearward movement of the wheel carrier 8 to move the wheel back to the platen 44 around which the paper is carried in a manner well understood in the art. It may be noted, however, that the carrier 8 is started rearwardly before the stop rack 34 comes into contact with one of the stop members 40, or in other words, during the rotation of the type wheel, this movement of the carrier being due to the coaction between the arms 22 of the vibrator 19 and the adjacent cam face 25 of the plate 9. The position of the parts at the moment of printing is clearly indicated in Fig. 4.

When the key is released the wheel carrier 8 and the parts connected thereto are stored to normal position by a primary retracting spring 45 located in a slot in the central frame member 6 and secured at its front end to said member, as indicated at 46, and at its rear end to a pin 47 depending from the wheel carrier 8, see Fig. 3^a. The key levers and keys are returned to normal position by retracting springs 48, the retractile movement of the levers being limited by stop members 49.

The ribbon mechanism constitutes an important feature of the present invention, the primary object being, as already stated, to effect a step-by-step advance of the ribbon in either direction without imposing the burden of the ribbon feed upon the keys. Depending from the top plate 39 adjacent to the opposite ends thereof are a pair of spool spindles 50, see Fig. 9, upon the lower ends of which rotate the ribbon spools 51 upon which the opposite ends of a ribbon 52 are reversely wound. That portion of the ribbon which is wound upon the respective spools is housed within a spool casing 53 having the form of a sheet metal cup having one or more vertical slits 54 in its side wall for the passage of the ribbon and secured to the spindle 50 as by a thumb screw 55 screwed into the lower end of the spindle and supporting the casing. The casing is held against rotation in any suitable way as for instance by flattening one side of the lower extremity of the spindle 50 and correspondingly forming the opening in the bottom of the casing, as indicated at 56 in Fig. 11.

Rotatable upon the feed spindle 50 above the ribbon spool is a hub or sleeve 57 retained against longitudinal movement on the sleeve by a ring key 58 and having secured to its lower end a ratchet crown or horizontally disposed ratchet wheel 59 preferably in the form of a metal disk bent to form an annular rib 60 upon the upper side of which ratchet teeth 61 are produced.

The member 59 affords a cover for the

spool casing 53 and constitutes the ribbon spool ratchet by the rotation of which, in a manner to be described, the adjacent ribbon spool 51 is rotated to feed the ribbon. To effect a driving connection between the ratchet member 59 and the spool 51 the former is provided with a lug 62 which engages in any one of a series of notches 63 formed in each end of the spool, see Figs. 9, 10 and 12. While a single notch 63 would suffice, it is preferable to form each end of the spool with a plurality of notches in order to facilitate assembling, since this construction renders it immaterial which end of the spool is uppermost and enables the lug 62 to drop into one of the notches 63 by slight rotary movement of the spool.

That portion of the ribbon 52 extending between the spools is preferably guided at opposite sides of the printing point by ribbon guides 64 preferably in the form of wire loops suspended from the inner sides of the key lever brackets 38, see Figs. 5, 7, and 13.

The means for rotating the ribbon spools comprises in addition to the spool ratchets 59, a pair of ribbon feeding pawls 65 carried by terminal arms 66 of a rock shaft 67 accommodated in a groove 68 in the under side of the top plate 39 and retained by the securing plates 69 of the brackets 38, see Fig. 7. The arms 66 of the rock shaft 67 are so spaced that when one of the pawls 65 is in engagement with one of the spool ratchets 59 the other pawl 65 will be out of engagement with the other ratchet, a longitudinal movement of the rock shaft 67 being necessary to effect a reversal of the feed by disengaging the engaged pawl from its ratchet and by engaging the disengaged pawl. To effect this longitudinal movement of the shaft 67 a handle or reversing pin 70 is extended from the middle of the rock shaft 67 through an opening 71 in the top plate. Thus when the operator desires to reverse the feed of the ribbon it is simply necessary to move the projecting portion of the reversing pin 70 to the opposite end of the slot or opening 71.

It will be noted that the rocking of the shaft 67 will oscillate the arms 66 and thus reciprocate the pawls 65, so that the engaged pawl will coact with its ratchet to rotate the latter and thus rotate one of the ribbon spools. The necessary rocking of the shaft 67 to accomplish this result is effected by the spindle 11 of the printing wheel. The spindle 11 is adapted to coact with a cam plate 72 extended rearwardly from the middle portion of the rock shaft 67, as shown in Figs. 6 and 7.

The cam plate 72 constitutes in effect a central arm of the rock shaft and is retained in the depressed position shown in dotted lines in Fig. 6 by a retracting spring 130

73 backed by the top plate 39 and bearing upon the upper side of the cam plate 72. In this depressed position of the plate 72 the pawls 65 are held retracted, but when the wheel carrier 8 is retracted by the spring 45 after the printing of a character the upper end of the spindle 11, as it moves back with said carrier, will engage the under side of the cam plate 72 thus elevating the latter and rocking the shaft 67 to advance the pawls 65 from the dotted position in Fig. 6 to the position indicated in full lines. Thus the burden of operating the ribbon feeding mechanism is imposed on the 10 retracting spring 45. When the next key is depressed and the spool carrier 8 moves rearwardly to print, the wheel spindle 11 rides out from under the cam plate 72 which drops back to the dotted position and 15 retracts the ribbon feeding pawls 65 for a repetition of the described operation. It may be noted in passing that the cam plate 72 is of such width, see Fig. 7, that its disengagement from the spindle 11 will not be affected by such movement of the shaft 67 and plate 72 as is necessary to effect a reversal of the ribbon feed.

Secured to the rear member 3 of the main frame as by a base flange 74 is a back wall 30 75 against the front face of which slides the back plate 76 of a platen carriage which, in addition to the plate 76, includes end members 77 and a feed rack 78 which like the back plate 76 extends between the end members but is located in a horizontal position at the lower front corner of the carriage. For the support of the rack 78 the main frame is provided with upstanding supporting or bearing lugs 79, see Figs. 2 and 5.

40 To facilitate the guiding of the paper around the platen, a paper guiding and clamping plate 80 is secured to the back plate 76 at the upper edge thereof and is carried under the platen and around to the front side thereof where its front edge is scalloped to form holding or clamping fingers 81, it being understood that the plate 80 is formed of resilient sheet metal. The 45 upper edge of this plate or guide 80 is bent over to form at the upper edge of the back plate 76 a hanger or guideway 82 which fits over the flanged upper edge of the back wall 75 relative to which it moves with the carriage.

55 To facilitate the feeding of the paper two feed rolls 83 extended through openings in the paper guide 80 and bearing against the platen are mounted on a rod 84 carried by the back plate 76. The advanced end of the paper as it passes rearwardly from the upper side of the platen is sustained by a folding paper table 85 pivotally mounted on a long pintle 86 afforded bearings in the end 60 members 77 of the carriage above the back

plate 76. When the table 85 is thrown back to the position shown in Fig. 5 its movement is limited by a projection 87, as shown. When the typewriter is not in use, however, the table 85 is swung to a position over the 76 platen. 88 indicates a bail-shaped swinging scale bar pivoted to the end members 77 of the platen and retained by light springs 89. 90 indicates a locating bracket or frame having pins which engage and hold the printing wheel during the printing operation in a manner understood in the art. 75

The step-by-step advance or feed of the carriage is effected by a feed dog 91 mounted on the wheel carrier 8 and arranged to 80 engage and advance the feed rack 78 in an obvious manner. The machine is also equipped with the usual margin stop devices and bell mechanism, the construction of both of which is well understood in the art and 85 need not be described.

It remains only to describe in detail the novel construction of the finger keys. As shown in Figs. 16 to 20 inclusive, each finger key comprises what is known as the key 90 top 92, the character plate 93 and the plate frame 94. The key top 92 is a horizontally disposed metal plate having a circular depression or sink 95 in the bottom of which is a comparatively long and narrow sub-sink 96 disposed diametrically of the depression 95 and transversely of the key lever 37. At the upper end of the key lever 37 is formed a tongue 97 which extends through an opening 98 formed by cutting 100 away the central portion of the sub-sink 96.

In assembling the parts the key top 92 is placed with the upper end of the key lever 37 abutting the under side of the depression 95 so that the key top rests upon the lever with the walls of the sub-sink dropped down upon the opposite sides of the lever and forming shoulders 99 which abut against the opposite sides of the lever, as shown in Figs. 17 and 20, to resist lateral displacement or rocking of the key top on its support. In order to rigidly secure the key top, that portion of the metal key lever which extends into the key top, to-wit the tongue 97, and perhaps a portion of the adjacent metal is punched down or riveted. The character plate 93 is merely a flat plate of any suitable material placed upon and conforming to the contour of the key top 92, and held in place by the plate frame 94. 110

The frame 94 extends continuously around the edges of the key top and character plate and is formed with a face flange 100 which overlies the margin of the character plate 93. The frame 94 is also formed with depending tabs 101 which are bent under the key top, as shown in Figs. 17 and 20, to retain the frame 94 and to cause the latter to securely clamp the character plate and key top together. 115 120 125 130

It is thought that from the foregoing, the construction, operation and advantages of the several described features of the invention will be fully understood, but I wish to 5 distinctly reserve the right to modify the novel features within the scope of the appended claims and to employ said features in other than the specified relation.

What I claim is:—

10 1. In a typewriter, the combination with a platen and type wheel, of wheel operating means including a slide having a graduated series of contact rolls and a series of key levers for operating said slide and coacting 15 with the contact rolls thereof.

15 2. In a typewriting machine, the combination with a platen and type wheel, of wheel operating means including a series of key levers and a wheel operating slide operated 20 by said levers, said slide having a series of lever guides and a graduated series of contact rollers each arranged to be engaged by a key lever.

25 3. In a typewriter, the combination with a platen and type wheel, of wheel operating mechanism including a series of key levers, a slide operated by said levers and provided with a series of parallel lever guideways and a series of contact rollers mounted in 30 said guideways.

35 4. In a typewriter, the combination with a platen and type wheel, of wheel operating mechanism including a series of key levers, a slide coacting with said key levers and having a series of parallel guideways for the levers, and a contact roller mounted in each guideway, the several contact rollers of the series being graduated as to size and mounted on a common axis.

40 5. In a typewriter, the combination with a type wheel and platen, of wheel operating means including a slide, and a series of operating levers therefor, adjustable guides for the slide, and anti-friction bearing elements interposed between the slide and guides.

45 6. In a typewriter, the combination with a type wheel and platen, of wheel operating

means including a slide having a series of lever guideways and graduated contact rollers mounted in said guideways, a series of key levers coacting with the contact rollers of the slide, and means facilitating the adjustment of the slide both laterally and longitudinally.

55

7. In a typewriter, the combination with a platen and type wheel, of wheel operating mechanism comprising a pair of reciprocatory slides each having a graduated series of contact elements, and a series of key levers associated with each slide, certain of said levers being arranged to coact with the graduated contact elements and movable to shift the slide.

8. In a typewriter, the combination with a platen and type-wheel, of wheel-operating mechanism including a pinion, an oscillatory vibrator geared thereto, a reciprocatory slide connected to the vibrator to swing the same and having a graduated series of anti-friction contact elements, guiding means for the slide, a series of key levers for operating the slide and arranged to engage the graduated contact elements thereof, and a rack 70 geared to the pinion and disposed to engage 75 the key levers.

9. The combination with a platen and printing wheel, of means for operating the wheel to print, said means including a pair of parallel reciprocating slides arranged at 80 opposite sides of the wheel and each having a graduated series of contact surfaces, a pinion arranged to revolve with the type-wheel, an oscillatory vibrator, and a rack 85 geared to said pinion, operating connections between the slides and the vibrator, and a series of key levers for operating each slide, said key levers being arranged to engage the graduated contact surfaces of said slides and to be engaged by the rack to limit the 90 rotative movement of the type-wheel.

In testimony whereof I affix my signature in presence of a witness.

HARRY A. FOOTHORAP.

Witness:

W. J. EVERETT.
